UNITED STATES PATENT OFFICE.

THOMAS R. KENNEDY AND EDWARD J. KING, OF ROCHESTER, NEW YORK,
ASSIGNORS TO COÖPERATIVE FOUNDRY COMPANY, OF SAME PLACE.

DESIGN FOR A FURNACE-FRONT.

SPECIFICATION forming part of Design No. 35,009, dated August 27, 1901.

Application filed July 22, 1901. Serial No. 69,334. Term of patent 7 years.

To all whom it may concern:

Be it known that we, THOMAS R. KENNEDY and EDWARD J. KING, citizens of the United States, residing at Rochester, in the county of Monroe and State of New York, have invented and produced a new and original Design for a Furnace-Front, of which the following is a full, clear, and exact specification, in connection with the accompanying drawing, forming a part thereof.

The drawing is a front elevation of a furnace-front embodying our design.

The design consists of a panel 1, substantially rectangular in form, rounding outwardly slightly and having the parallel sides bounded by a molding 2, which also extends over the top of the furnace-front, said top portion being curved upwardly over its central portion. The furnace-front is divided 15 transversely into an upper and lower section by a horizontally-extending molding 3, and located centrally in the upper section is the door 4. Across the top of the door is a scroll-and-leaf ornamentation 5, and beneath the 20 latter is a panel surrounded by a molding 6,

provided with the ornamentation 7, which extends above and at the sides of the damper-openings 8. The upper section is provided with conventional scroll-and-leaf ornamentations 9 in relief, extending below and at 30 the sides of the door 4, and at the upper corners of the section are the ornaments 10. Arranged beneath the molding 3 and across the top of the lower section are the scroll-and-leaf ornaments 12, extending upon each side 35 from the center, and below the latter is the door 13, having upon its sides the relief ornaments 14. The door 15 is ornamented, as shown at 17, upon its outer edges, and at the bottom corners the lower section of the furnace-front are located the scroll-and-leaf ornaments 18.

We claim—

The design for a furnace-front substantially as herein shown and described.

THOMAS R. KENNEDY.
EDWARD J. KING.
